MOORING DEVICE

Walter L. Schuelke, Milwaukee, Wis.

Application January 30, 1946, Serial No. 644,399

1 Claim. (Cl. 114—230)

1

This invention relates to improvements in mooring devices and more particularly to a novel means for mooring a boat to a dock or other fixed object.

An object of the invention is to provide a device of the type which may quickly be attached to the boat, which may be as readily released, but which will not readily jam or release by itself.

Another object of the invention is to provide means of the type which may be dropped out of the way when the boat is not being moored.

Other and further objects will appear as the description proceeds, reference being had to the accompanying drawing, in which:

Fig. 1 is a plan view of the mooring means in use.

Fig. 2 is a side view in elevation of a sleeve.

Fig. 3 is a front view in elevation of the same.

Fig. 4 is a top view of the mooring end of the rear mooring attachment.

Fig. 5 is a side view of the same, showing the boat eye in section.

Fig. 6 is a side view of the front mooring attachment.

Referring more particularly to the drawings, the numeral 10 refers to a dock or pier, which has, for the rear mooring attachment 11, the journal sleeves 12, which are secured to the dock by any suitable means and are in horizontal axial alignment, to accommodate the cross segment 13 of attachment 11. Integral with cross segment 13 are the arm 14 and the diagonal arm 15, the outer ends of which are welded together or otherwise fastened. The arm 14 has an integral downward extension 16, adapted for engagement in the eye 17 on the rear end of boat 18. The arm 15 after juncture with arm 14 adjacent their outer ends continues on horizontally to form a short extension 19.

An eye 20 on dock 10 engages freely the eye 21 on the front mooring rod 22, which latter has a downward extension 23 at the outer end thereof, and the short continuing protruding portion 24. The extensions 16 and 23 are provided with apertures at 24 and 25 thereof, to provide accommodation for the use of a padlock or the like, if desired.

2

The extension 24, during rolling of the boat will prevent catching of the rod 22 in the boat eye 26, as might happen if extension 24 were absent, and the same is true of extension 19 on the rear mooring attachment 11.

In use, the attachment 11 and the arm 22 will normally hang downwardly into the water and out of the way of boats passing or approaching the dock 10. When a boat is to be moored, the downward extension 23 is inserted into the bow eye 26, and the downward extension 16 is inserted into the stern eye 17 on the boat. Padlocks may or may not be inserted as desired in the eyes at 24a and 25.

It will be understood that the device is capable of many modifications in structure and design, without departing from the spirit of the invention, within the scope of the appended claim.

Having thus described my invention, what I claim and desire to secure by Letters Patent of the United States, is:

A boat mooring apparatus comprising a triangular member having its apex at the boat end thereof, the two side legs of said triangular member at the point of convergence continuing parallel for a portion of their lengths, one leg terminating in a downwardly directed element having a padlock-receiving eye at its lower end, and the other leg projecting in a horizontal extension beyond said downwardly directed element and a boat eye to be engaged by the downwardly directed element, and a weld joint fixing said legs at the area of contact.

WALTER L. SCHUELKE.
